HOUSING FOR A SEWAGE PUMP STATION OR THE LIKE

Simpson V. Prator, P.O. Box 117, Mineral Wells, Tex.

Filed Aug. 6, 1959, Ser. No. 57,082

Term of patent 14 years

(Cl. D13—1)

FIG. I is a perspective view of the housing for a sewage pump station or the like showing my new design;

FIGURE II is a side elevational view thereof;

FIGURE III is a top plan view thereof; and

FIGURE IV is an elevation thereof as seen from the right of FIG. II.

I claim:

The ornamental design for a housing for a sewage pump station or the like, substantially as shown.
